ATTORNEY

UNITED STATES PATENT OFFICE

94,457

DESIGN FOR A CASE FOR MICROSCOPE AND ACCESSORIES

Milton C. Williamson, Rochester, N. Y., assignor
to Bausch & Lomb Optical Company, Rochester, N. Y., a corporation of New York

Application May 17, 1934, Serial No. 51,822

Term of patent 7 years

To all whom it may concern:

Be it known that I, Milton C. Williamson, a citizen of the United States, and a resident of Rochester, county of Monroe, and State of New York, have invented a new, original, and ornamental Design for a Case for Microscope and Accessories, of which the following is a specification, reference being had to the accompanying drawing, forming a part hereof.

Fig. 1 is a front perspective view, in a closed position, of a case for microscope and accessories; and

Fig. 2 is a front perspective view of the same, in an open position, showing my new design.

The ornamental features of my design comprise

an ornamental figure on the outside of the cover, two inner doors of substantially equal size, one on each side of the case, similar appearing structure on the inner side of each door, and racks and supports symmetrically arranged within the case. The cover has an ornamental border on its outer and inner faces and the same border is on the inner face of each door. The ends of the case are plain and the back is either plain or ornamented as on the front.

I claim:

The ornamental design for a case for microscope and accessories as shown and described.

MILTON C. WILLIAMSON.
